FIG.5

FIG. 6

FIG. 7

FIGURE 1 is a bottom perspective view of an outdoor lighting fixture, showing our new design.

FIGURE 2 is an elevational view showing the bottom of the fixture.

FIGURE 3 is a top plan view of the fixture.

FIGURE 4 is a side elevation of the fixture.

FIGURE 5 is an elevational view looking at the left end of FIGURE 1.

FIGURE 6 is a sectional view of the fixture taken along lines 6-6 of FIGURE 2; and

FIGURE 7 is a sectional view of the fixture taken along lines 7-7 of FIGURE 2.

The end of the fixture not shown is substantially the same in appearance as the end shown by FIGURE 5. The light tubes are shown in broken lines in FIGURES 1 and 2 for illustrative purposes only.

We claim:

The ornamental design for an outdoor lighting fixture, as shown and described.
